Primary Examiner — Sandra Snapp*Assistant Examiner* — Bryan N. Melvin(74) *Attorney, Agent, or Firm* — Greenberg Traurig, LLP(57) **CLAIM**

The ornamental design for a sealed connector receptacle as shown and described.

DESCRIPTION

FIG. 1 is a top, front perspective view of a sealed connector receptacle showing my new design;

FIG. 2 is a bottom, rear perspective view thereof;

FIG. 3 is top plan view thereof;

FIG. 4 is a bottom plan view thereof;

FIG. 5 is a left side elevational view thereof;

FIG. 6 is a right side elevational view thereof;

FIG. 7 is a rear side elevational view thereof; and,

FIG. 8 is a front side elevational view thereof.

The short dash-short dash lines in the drawings depict features of the sealed connector receptacle that form no part of the claimed design. The long dash-short dash lines in the drawings indicate a boundary of the claimed design.
